EDWARD L. AIKEN, OF SPRINGFIELD, MASSACHUSETTS.

DUST-CAP FOR VALVE-STEM!

1,220,809.

Specification of Letters Patent. Patented Mar. 27, 1917.

Application filed June 24, 1915. Serial No. 36,089.

To all whom it may concern:

Be it known that I, EDWARD L. AIKEN, a citizen of the United States of America, and resident of Springfield, in the county of Hampden and State of Massachusetts, have invented certain new and useful Improvements in Dust-Caps for Valve-Stems, of which the following is a full, clear, and exact description.

10 This invention relates to improvements in dust caps, for the valve stems of pneumatic tires, of a kind having the capability of removal from the stem, and the reengagement thereof with the stem without the necessity of repeated and long continued turning of the cap.

The object of the invention is to provide a dust cap, of the class referred to, which is susceptible of the desired quick and easy 20 manipulation for connection and disconnection with the valve stem, which is simple and inexpensive of construction, which is devoid of features whereby it is liable to become deranged or ineffective, which when 25 engaged with the stem is reliably interlocked therewith, and without liability of accidental disengagement, and which is generally desirable and acceptable both from the standpoint of the manufacturer and that 30 of the user.

The invention is described in conjunction with the accompanying drawings and is set forth in the claims.

In the drawings:

35 Figures 1 and 2 are substantially central vertical sections, enlarged, showing the dust cap with parts thereof in slightly different relations which they are permitted to have in relation to the valve stem and a portion of the felly or rim of the wheel.

Figs. 3 and 4 are cross sectional views taken on lines 3—3 and 4—4 respectively on Fig. 2, and as seen in the directions indicated by the arrows.

45 Fig. 5 is a perspective view of a part or appurtenance of the dust cap.

In the drawings, A represents the valve stem which is almost universally used in connection with the inner tubes of pneu-

matic tires, is reduced or slabbed on opposite sides and screw threaded on its side portions between and interrupted by the slabbed portions.

B represents the dust cap of elongated and tubular formation generally employed, but it has at its lower end portion internally interrupted threads $\alpha\alpha$ which in the formation of the cap may be produced by the inward displacement of the opposite sides of the lower end portion of the walls of the cap to form opposite inward protuberances which are formed screw threaded by a suitable tap.

This formation is indicated in Fig. 3. The dust cap is made with an external 65 downwardly facing shoulder b above its lower end, and with an external upwardly facing shoulder d above the shoulder b .

C represents the collar having an encircling engagement about the dust cap and capable of revoluble movement and a limited endwise movement relatively to the cap.

The collar is made with an internal flange f extending across the lower end of the dust cap, and its upper end portion is inwardly turned or "spun" to produce an annular flange g which by engagement with the aforementioned shoulder d of the dust cap prevents the disconnection of the collar from the dust cap. When the cap is slid over the stem the collar has a nonrotative engagement therewith, because of the non-circular formation of the aperture c in the flange f .

D represents a spiral spring enclosed 85 within the collar forming enlargement e within the collar, encircling the lower portion of the dust cap and in compression between the downwardly facing shoulder b of the dust cap and internal part or shoulder i of the collar.

The dust cap is normally, or when not in its screw engagement with the valve stem, outwardly forced as represented in Fig. 2, by the reaction of the spring and as limited 95 by the engagement of the upwardly facing shoulder d with the inwardly turned upper end portion or flange g of the collar; and

the range of movement which the dust cap may have relatively to the collar will be apparent by a comparison of Figs. 1 and 2.

Assuming that the dust cap is to be applied about and screw engaged with the threaded valve stem, the cap is placed in relation to the valve stem with the opposite internal interrupted threads in matching relation with the slabbed or flattened sides of the valve stem,—the dust cap and its collar being in the distended relations indicated in Fig. 2.

Now as it is not probable that the threads *a* internally in the dust cap under the rotative movement of the latter will be exactly alined with the threads of the valve stem, the endwise movement of the cap against the yielding pressure of the spring enables one to quickly "catch the threads" of the stem by the manipulation combining a downward and a rotative force to the cap.

So soon as the internal threads of the cap match and engage with the interrupted threads of the stem, the spring remains, by its pressure on the cap upwardly, as a factor for exerting a force to maintain the sides of the interengaged threads under a constant bind, preventing tendency, due to rattling or vibration of the threads, to work to disengagement and permit the dust cap to become disconnected with the valve stem.

The peripheral portion of the dust cap, such advantageously as that adjacent and next below the upwardly facing shoulder *d* is made of an eccentric form as indicated at *j* in Fig. 3, and the collar is provided with an inwardly projecting member *m* for a binding impingement against said eccentric portion *j* as the cap is turned relatively to the collar.

When the dust cap is brought into relation the nut may be turned as by a wrench or pinchers to exert a powerful force in an upward direction against the collar, through the engagement of the internal flange *f* of the latter against the lower end of the dust cap to transmit such force to the latter and effectively crosswise bind the interengaged threads of the cap and stem.

The felly constitutes a base support for the collar through the medium of the nut *G* which is to be regarded as an adjustable appurtenance thereof; but in cases where the nut is omitted the collar would receive its base support directly against the felly.

The device inclusive of the nut is regarded as much the best, as the powerful wrench-applied force exerted on the nut and through the collar to force the cap endwise, after being screw engaged on the stem is effective to prevent disconnection of the cap from the stem excepting by a reversely applied powerful force on the nut.

The provision of the spring *D* is more especially desirable for the reason that it renders the device, for its connection with the stem, a "one handed" one, that is were it omitted, it would require two hands to manipulate the device to interlock the interrupted threads of the cap with those of the stem, as by gravity or hand pressure when the cap and collar were slid onto the stem the cap would naturally bottom on the flange of the collar and to catch the thread it would be necessary to employ one hand to hold the collar down while the other hand were used to effect the relative endwise movement to catch the thread; but by the provision of the spring the cap and collar when slid down onto the slab sided stem, as may be done with one hand, are in axially distended relations (Fig. 2), and the employment of the one hand only is then sufficient to depress the stem relatively to the collar to effect the matching of the threads, and by the partial turn of the cap, the interlocking thereof. Then, of course, the turning of the nut in the proper direction relatively upwardly sufficiently moves the collar so that through its flange *f* it exerts the upward crowding action of the cap relatively to the stem for the powerful locking of the cap on the stem.

I claim:

1. In combination, a valve stem having interrupted threads thereon, a dust cap having interrupted internal threads for quick detachable engagement with those of the stem, said cap having a peripheral cam surface adjacent its lower portion, and a collar having encircling engagement about the lower end of the cap, having a limited endwise movement relative thereto and an inwardly pressed protuberance on the collar for endwise and transverse movement on the cam surface of the cap, said collar having means preventing rotation thereof on the stem.

2. In combination, a valve stem having interrupted threads thereon, a dust cap having interrupted internal threads for quick detachable engagement with those of the cap, said cap having a peripheral base flange, a collar engaging over the flange of the cap for rotative and limited endwise movement, means preventing rotation of the collar on the stem, said cap having a part adapted to be brought into bearing relation with the collar when the cap is threadedly engaged with the stem, and means for exerting endwise thrust on the collar for transmission to the cap to effect a corresponding binding between the threads of the cap and stem.

3. In combination, a wheel felly, and a valve stem passing therethrough and having interrupted threads, a dust cap having interrupted threads for quick detachable en-

gagement with those of the stem, a collar connected with the cap for limited endwise movement relative thereto, a spring means holding the collar and cap extended, said cap when threadedly engaged with the stem being brought into positive bearing contact with the collar, the latter having an exteriorly threaded portion, and a nut engaged with the collar threads and adapted to bear

against the felly to exert endwise thrust 10 through the collar on the cap for binding the threads of the cap and stem.

Signed by me at Springfield, Mass., in presence of the subscribing witness.

EDWARD L. AIKEN.

Witness:

G. R. DRISCOLL.
